UNITED STATES PATENT OFFICE.

STEPHEN TAFT, OF MILLBURY, MASSACHUSETTS.

DEVICE FOR STRETCHING WIRES.

SPECIFICATION forming part of Letters Patent No. 408,997, dated August 18, 1889.

Application filed April 25, 1889. Serial No. 308,504. (No model.)

To all whom it may concern:

Be it known that I, STEPHEN TAFT, a citizen of the United States, and a resident of Millbury, in the county of Worcester and 5 State of Massachusetts, have invented certain new and useful Improvements in Devices for Stretching Wires; and I do hereby declare that the following is a full, clear, and exact description of the invention, which will enable others skilled in the art to which it appertains to make and use the same.

The invention relates to improvements in wire stretching and tightening tools or devices, and while it can be used to stretch and 15 tighten extended wires of any kind—such as fence-wires and clothes-lines—it is more particularly adapted for the use of linemen in placing telegraph and other electric wires.

The tool which is the subject of invention 20 is intended to grip, hold, and stretch the wire without the necessity of the operator using his hands; and it consists in the construction and novel combination of parts hereinafter described, illustrated in the drawings, and 25 pointed out in the appended claims.

Figure 1 of the drawings represents a perspective view of the tool complete, including the strap and a rubber band surrounding the shanks of the tool. Fig. 2 represents a front 30 or face thereof, showing the arrangement of the notches in the dogs of the jaws. Fig. 3 represents a perspective view of one of the dogs detached. Fig. 4 represents a longitudinal section in the line $x-x$ of Fig. 1, a spring 35 being used instead of the rubber band. Fig. 5 represents an edge view of the outer or jaw portion of the tool; and Fig. 6 is a detail view, in perspective, of the pivot-pin.

Referring to the drawings by letter, A designates the metallic gripping portion or nippers of the tool, composed of nearly similar 40 opposed sections B C, respectively.

The section B consists of the flattened and outwardly and laterally extended jaw b and 45 the shank b' , curving inward from the jaw in the manner usual with nippers and provided in said curved portion with the longitudinal slot b^2 . The said slot is provided with a longitudinal curved shoulder within it, as shown 50 in Fig. 4, and the shank beyond the bent or curved portion runs almost parallel to the

similar part of the shank of the opposite section.

b^3 b^3 are transversely-perforated lugs which stand from the inner surface of the shank 55 b' —one just inward from the curved portion thereof and the other at the end of the shank—and b^4 b^4 are metal loops which are attached to said lugs by screws b^5 , that pass through the perforations in said lugs and through 60 similar registering-perforation in the ears of the loops, which ears lie against opposite sides of the corresponding lugs. The transverse bars of the said loops are surrounded by anti-friction sleeves b^6 , as shown. 65

The jaw b has on its inner or facing edge a transverse groove or open-ended recess b^7 , the rear wall of said recess extending upwardly above the horizontal plane of the other portion of the jaw. 70

The section C consists of a jaw c and a shank c' , similar in contour to those of the section B, which shank passes through the slot b^2 of the opposite section. The shank c' is provided about midway between the lugs b^3 75 with a similar instanding perforated lug c^3 , to which is hung a loop c^4 , similar to the loops b^4 , by means of a screw c^5 , the loop being provided with the anti-friction sleeve c^6 . The lug c^3 has at its base a transverse recess, for 80 a purpose hereinafter explained.

The jaw c is provided with a transverse groove or recess c^7 , the rear wall thereof being extended, as shown. The outer surfaces or faces of the two jaws are inclined or bevelled outward from their meeting edges to 85 give clearance when gripping.

D is a pivotal pin passing through registering openings in the curved portions of the two shanks, provided on one end with a flat- 90 tened nearly-rectangular head d , the upper edge of which rests against and is supported by a shoulder on the inner surface of the jaw B, and having its shank extended for some distance outward from the tool on the opposite side, and provided with the long cut-away portion or rabbet d' , having its shoulder rounded, as shown. 95

E are grippers or dogs fitted, respectively, into the recesses b^7 c^7 , the flanges e of 100 the dogs entering the recesses, while their main portions e' rest upon or impinge against

- the horizontal flat portion of the jaws. The said main portions are nearly rectangular in cross-section, and their outer surfaces are preferably flush with the faces of the jaws.
- 5 The meeting edges of the dogs are preferably provided with similar longitudinal grooves F, but may, if desired, be flat, and are crossed at proper points at right angles by the rounded notches f, which meet and register when the jaws are closed, and the pairs of which may be of different sizes. The said notches are, however, preferably arranged in such manner that an equal number of pairs stand on each side of a central pair at equal distances 10 therefrom, all of which pairs may differ in size to grip properly wires of different diameters. The grooves and notches cause the meeting edges of the dogs to have somewhat of a toothed appearance.
- 20 G is a strap of suitable length having a buckle g on one end and a series of perforations to engage said buckle extending from the opposite end, so that the loop of the strap, when the buckle is engaged, may be made 25 larger or smaller, as desired.
- 25 The strap G has its middle portion passed over the sleeve b⁶ of the loop b⁴, attached to the lug b³, adjoining the slot b². Thence both ends of the strap pass under the anti-friction 30 roller of the loop c⁴, attached to the shank c³, and thence over the friction-roller of the loop attached to the end of the shank b¹. The ends of the strap are then buckled together, making as large a loop as is necessary. The 35 dogs may be removed from the jaws and other dogs attached having differently arranged and sized notches. These dogs are held in place by means of the flanges e thereof, which enter the recesses b⁷ c⁷, and fit 40 close enough to prevent their dropping out as the tool is manipulated.
- H is a curved plate-spring having one end bent under the curved shoulder in the slot b², and secured there by screws or rivets passing 45 through openings that extend from the outer surface of the shank b¹, and the other end passed into the recess in the base of the lug c³, so that both ends of the spring are attached.
- 50 When the jaws and shanks are parted to grip a wire, the spring is straightened and put under tension thereby, and it assumes its normal curved shape and automatically closes the jaws tightly on the wire, when the handles are released.
- 55 Instead of using the spring, a strong rubber or other elastic band can be passed around the shanks of the tool, as shown in Fig. 1, which band will answer the same purpose.
- 60 In practice a line-man, having ascended a telegraph-pole, can put the strap G around his body, and, having engaged the wire to be operated on in the manner described, can, by simply leaning outward from the pole, cause 65 the wire to be more firmly grasped, and can thereby extend and stretch the wire for the desired distance, having his hands free at the

time. The drawing outward of the strap, as is obvious from the described construction, closes the shanks and the dogs more closely, 70 and prevents the latter from slipping on the wire. The operator having his hands free, can then easily use a splicer, of any suitable construction, to connect the end of the gripped wire with that of an adjoining wire. The 75 operator can similarly splice the ends of the wires when on the ground, for by leaning backward he can stretch the gripped wire to the necessary distance. The weight of the operator's body in both cases acts to stretch 80 the wire. Two wires can also be twisted together by the tool, for by inserting the ends of the wires in two different pairs of notches and turning the tool the said ends will be twisted on each other. The extended shank 85 and the head of the pivot-pin D will bear on the wire passed through adjacent notches and further prevent slipping.

Having described my invention, I claim—

1. The combination, with the nippers having their shanks provided with registering openings, of the pivotal bolt provided with a flattened nearly-rectangular head, the lower edge of which rests against and is supported by a shoulder on the inner surface of the lower 95 jaw of the nippers, said pivotal bolt having its shank provided with a long cut-away portion or rabbet, substantially as set forth.

2. The combination, with the nippers A, composed of the pivoted sections B C, the section B having loops b⁴ attached to its shank, respectively, near the upper and lower ends thereof, and the section C having the similar loop c⁴ attached to its shank at a point between the loops b⁴, and the spring H, attached 100 at the upper end to the shank of the section B and at its lower end to the shank of the section C, of the strap G, passing, as described, through said loops and having the buckle g at one end, and the series of perforations g' 110 for the tongue of said buckle extending inward from the opposite end, substantially as specified.

3. The combination, with the strap G, of the nippers A, composed of the sections B and C, each composed of a shank and a flattened laterally-extended jaw, which jaws incline slightly outward from their meeting edges, the pivot-pin D, having a flattened head and an extended and rabbeted shank, the loops b⁴, attached to the shank of the section B, the loop c⁴, attached to the shank of the section C, the detachable dogs E E, provided with the longitudinal grooves F, and the transverse notches f f in their meeting edges, and the 125 curved plate-closing spring H, substantially as specified.

4. The combination, with nippers provided with shanks, the shank of the upper nipper passing through a slot in the lower shank, 130 of a curved flat-plate spring disposed between the same, said spring having its forward end bent under and secured to a curved shoulder in the slotted shank, substantially as set forth.

5. The combination of the nippers composed of two opposing sections and suitable shanks, the lower shank passing through a slot in the upper shank, the latter being formed or provided at opposite points of its length with depending perforated lugs, metal loops having the ears thereof perforated, said perforations registering with the perforations in the lugs, the transverse bars of said loops being provided with anti-friction sleeves, the screws for attaching said loops to the lugs, the perforated lug formed or provided upon the lower shank, the lower loop provided with an anti-friction sleeve, and the strap passing over the anti-friction sleeves of the loops, substantially as set forth.

6. The combination of the nippers composed of two opposing sections and suitable shanks, the lower shank passing through a slot in the upper shank, the latter being formed or provided at opposite points of its length with depending perforated lugs, metal loops having the ears thereof perforated, said perforations

registering with the perforations in the lugs, the transverse bars of said loops being provided with anti-friction sleeves, the screws for attaching said loops to the lugs, the perforated notched lug formed or provided upon the lower shank, the curved flat-spring plate disposed between the two jaws of the nippers, said spring having its forward end bent under and secured to a curved shoulder in the slotted shank, and having its rear end passing into the notched lug upon the lower shank, the lower loop provided with an anti-friction sleeve, and the strap passing over the anti-friction sleeves of the loops, substantially as set forth.

In testimony that I claim the foregoing as my own I have hereunto affixed my signature in presence of two witnesses.

STEPHEN TAFT.
